PAIR OF SPECTACLES

Albert G. McNeill, Maple Glen, Pa., assignor to Bachmann Bros., Inc., Philadelphia, Pa., a corporation of Pennsylvania

Filed Oct. 17, 1962, Ser. No. 72,151

Term of patent 14 years

(Cl. D57—1)

Fig. 1.

Fig. 2.

Fig.3.

Fig.4.

Fig.5.

FIGURE 1 is a front perspective view of a pair of spectacles showing my new design;

FIGURE 2 is a rear perspective view thereof;

FIGURE 3 is a top plan view thereof;

FIGURE 4 is a bottom plan view thereof; and

FIGURE 5 is a side elevational view thereof.

The temples are shown broken away in FIGURES 3 and 4 for convenience of illustration.

The characteristic features of my design for the pair of spectacles disclosed reside in the specific configuration of

the lens portions in association with the frame at the ends thereof and the adjacent temple portions as shown.

I claim:

The ornamental design for a pair of spectacles, as shown and described.
